(57) **CLAIM**

The ornamental design for a seal installation tool, as shown and described.

DESCRIPTION

FIG. 1 is a perspective view of a seal installation tool showing my new design;

FIG. 2 is a front section view thereof, taken from line 2, 3 in FIG. 4;

FIG. 3 is an exploded section view thereof, not including the seal, taken from line 2, 3 in FIG. 4;

FIG. 4 is a front view of the seal installation tool of FIG. 1;

FIG. 5 is a first end view thereof;

FIG. 6 is a second end view thereof;

FIG. 7 is a perspective view of a guide of the seal installation tool of FIG. 1;

FIG. 8 is a first end view thereof;

FIG. 9 is a second end view thereof;

FIG. 10 is a perspective view of a piston of the seal installation tool of FIG. 1;

FIG. 11 is a first end view thereof;

FIG. 12 is a second end view thereof;

FIG. 13 is a perspective view of a plunger of the seal installation tool of FIG. 1;

FIG. 14 is a first end view thereof; and,

FIG. 15 is a second end view thereof.

The broken lines in the Figures are for the purpose of illustrating unclaimed portions of the seal installation tool and form no part of the claimed design. The shade lines in the Figures show contour and not surface ornamentation. The design is directed to the tool shown in FIGS. 1–6. The components of the tool are shown separately in FIGS. 7–15 to further illustrate aspects of the tool.
